ANTENNA

Richard D. Bogner, 4 Hunters Lane,
Roslyn, N.Y. 11576

Filed Mar. 21, 1967, Ser. No. 6,381

Term of patent 14 years

(Cl. D26—14)

FIG. 1 is a rear perspective view of an antenna showing my new design, with the mast element broken away to indicate indeterminate length;

FIG. 2 is an enlarged top plan view thereof;

FIG. 3 is a fragmentary rear elevation thereof; and

FIG. 4 is a fragmentary front elevation of the antenna.

I claim:

The ornamental design for an antenna, substantially as shown and described.
